UNITED STATES PATENT OFFICE

HOWARD POTTER, OF YOUNGSTOWN, OHIO

DESIGN FOR A FLORAL BASKET

Application filed May 16, 1930. Serial No. 35,663. Term of patent 14 years.

To all whom it may concern:

Be it known that I, HOWARD POTTER, a citizen of the United States, residing at Youngstown, in the county of Mahoning and State of Ohio, have invented a new, original, and ornamental Design for a Floral Basket, of which the following is a specification, reference being had to the accompanying drawing, forming a part thereof.

showing my new design; and Figure 2 is a top plan view thereof.

The body of the basket is formed from a single rectangular piece of thin gage sheet metal which is bent to form a bottom and sides as shown in the drawings.

I claim:

The ornamental design for a floral basket, as shown and described.

HOWARD POTTER.
